[57] **CLAIM**

The ornamental design for a fishing line dispenser and coiled line therefor, as shown and described.

DESCRIPTION

FIG. 1 is an exploded front and top perspective view of my fishing line dispenser and coiled line therefor;

FIG. 2 is a front-elevational view thereof;

FIG. 3 is a rear-elevational view thereof;

FIG. 4 is a top-plan view thereof;

FIG. 5 is a bottom-plan view thereof; and,

FIG. 6 is a right-side elevational view thereof, it being understood that a left-side elevational view is mirror symmetrical thereto.
